(57) **CLAIM**

The ornamental design for a card reader mounting bracket, as shown and described.

DESCRIPTION

FIG. 1 is a top perspective view of a card reader mounting bracket showing our new design.

FIG. 2 is a right elevation thereof.

FIG. 3 is a left side elevation thereof; and,

FIG. 4 is a front elevation thereof.

The broken lines in the drawings form no part of the claimed design. Surfaces not shown form no part of the claimed design.
